RETAINING DEVICE.

1,226,705.

Specification of Letters Patent. Patented May 22, 1917.

Application filed May 25, 1914. Serial No. 840,749.

To all whom it may concern:

Be it known that I, AUGUST R. SCHENKY, a citizen of the United States, residing at Somerville, in the county of Middlesex and 5 State of Massachusetts, have invented certain new and useful Improvements in Retaining Devices, of which the following is a specification, reference being had therein to the accompanying drawing.

10 This invention relates to retaining devices, and is herein illustrated for convenience as applied for the purpose of retaining the bobbin within the shuttle of a lock stitch sewing machine, although obviously the invention might be employed for 15 analogous purposes. More especially this invention relates to the class of retaining devices for sewing machine shuttles or bobbins involving an arm or retainer which is pivoted adjacent to the shuttle box and is adapted to be swung between open and closed positions, so that it properly serves to hold the bobbin in the face of the shuttle during the operation of the machine and 20 may be opened when the machine is not operating, so as to permit inspection, replacement and repair.

An object of the present invention is to 30 generally improve and simplify retaining devices of the kind referred to and to provide an improved and simple means of normally effecting the locking of the retainer in closed position. Another object is to provide a novel and improved structure better 35 than those heretofore known whereby, with the use of a single handle or operating device, the retainer may be both opened and shut, and when shut may be both locked and unlocked, thus dispensing with the need 40 of the operator employing both hands for opening or closing the retainer. Other objects hereof will be elucidated during the hereinafter following description of the present invention.

45 To the attainment of the above recited objects, the present invention consists in the novel features of combination, construction, arrangement and detail referred to and illustrated in the accompanying description and 50 drawings.

In the accompanying drawings forming a part hereof Figure 1 is a top plan view of an illustrative embodiment of the present

invention showing it applied to the retaining of a bobbin within a rotary shuttle, the 55 retainer being in closed position.

Fig. 2 is a view similar to Fig. 1 with the retainer in open position.

Fig. 3 is a front elevation with the parts 60 adjusted as in Fig. 1.

Fig. 4 is a partial horizontal section taken on the plane 4—4 of Fig. 3.

Fig. 5 is a partial vertical section taken on the plane 5—5 of Fig. 1.

Fig. 6 is a partial horizontal section taken 65 on the plane 6—6 of Fig. 3.

The present invention includes the novel combination with the retainer swingable between open and closed positions, of a brace which is eccentrically pivoted to the retainer, or, what is the same thing, to a part rigid with the retainer, together with a suitable means that is operative when the retainer is closed and which serves to block the pivoted brace against endwise movement 70 whereby the retainer is locked closed, but is able to be opened by displacing the brace. 75

The invention also includes the combination with such retainer, brace and blocking means, of a single handle which is adapted 80 both to swing the brace into or out of the blocked position, and, when the brace is out of blocked position, to swing the retainer open or shut; and specifically such handle is connected to the brace, and acts through 85 the brace for swinging the retainer.

Referring more specifically to the drawings, a fixed portion 10 of the sewing machine frame supports the fixed shuttle box 11, in which rotates the circular shuttle 12 90 which in turn carries the bobbin 13. The bobbin has a vertical projection 14 provided for the purpose of engaging with and being retained in position by the recessed portion or head 15 of the swinging arm or retainer 16. Figs. 1 and 3 show the parts in their normal position, and in this position the shuttle 12 may be rotated or oscillated in any well-known manner, the bobbin 13 being held by the retainer 16 in either or both 100 of two ways, namely, held against coming out of the shuttle and held through the projection 14 against rotation. It will be understood that the projection 14 and the recess in 15 have such relation that the under- 105 thread or needle thread of the machine can

be passed around the shuttle in forming each stitch so as to interlock with the shuttle thread provided by the bobbin.

With the retainer 16 are comprised the following parts rigid therewith and substantially a part thereof, namely, the vertical fulcrum shaft 17 formed with shoulders or steps to give it greater solidity of fitting, and, at the upper part of the fulcrum shaft, 10 an enlargement 18 which may be considered as a crank disk, as it affords the means for an offset or eccentric connection between the retainer and the brace, to be hereinafter described. The parts 16, 17 and 18, being 15 rigid, swing together. Their further details will be later described.

A novel and important element of the present invention is the brace 20 shown in the form of a strut, it being pivotally connected to the retainer at an eccentric point 20 and adapted to swing, as will be hereinafter described, into and out of its blocked position. Instead of connecting the brace 20 directly to the swinging arm portion of the retainer, it is shown pivoted at the top side 25 of the crank disk 18, which is rigid with the retainer. Such a pivotal connection is conveniently afforded by a crank pin or stud 21, preferably integral with the brace 20 and fitting in a circular recess in the top of the crank disk 18. The free or swinging end 22 of the brace is the part thereof which is adapted to be blocked to preclude opening movement of the retainer when closed.

Referring to Fig. 1, it is obvious that, if the brace or strut 20 can be held or blocked against movement when the retainer is closed, such action will effect the locking of the retainer. While the relative arrangement of the parts might be considerably altered, the crank pin 21 in Fig. 1 is shown located to the rear of the fulcrum shaft 17, forming the axis of swinging of the retainer, and the brace 20 in this figure extends directly to the right. If now the right-hand end 22 of the brace be held so as to prevent endwise movement of the brace, this will render the crank pin 21 absolutely immovable, so that the retainer becomes securely locked. The following constitutes a convenient blocking means acting at the free end 22 of the brace to prevent endwise movement of the brace.

A blocking abutment 24 is shown consisting of a member preferably rigid with the frame and presenting at its left side a vertical surface standing substantially at right angles to the direction of the brace 20 when the retainer is closed and the brace blocked. 55 The abutment 24, in fact, constitutes the blocking means, the brace fitting snugly between the crank stud 21 and the abutment, being so dimensioned as to hold the parts tightly in position when swung into place, 60 the abutment holding the brace against end-

wise movement and the brace locking the retainer against any movement.

On the other hand, one merely has to swing the brace 20 forwardly to throw it out of blocked position and to permit or cause the opening of the retainer.

It will be seen that the upper side of the disk 18 is provided with a depressed portion or recess upon which the brace 20 is pivoted and an upstanding or elevated portion 25, 75 which, as seen in Fig. 4, limits the swinging movement of the brace. A cover plate 26 of circular form is secured on top of the elevated part 25 of the crank disk, where it is secured by a screw 27 and by engagement with the stud 21 which projects upwardly to a point above the cover plate. In this way the brace is inclosed and protected, and the upwardly projecting stud thereof affords a means of operating it. The stud 21 above where it projects through the cover plate 26 is keyed, and has fitted over it the apertured hub of a lever 28 forming part of an operating handle 29, which, by the described construction, is rendered rigid 80 with the brace 20 and able to swing it into and out of blocked position.

By the described arrangement it will be seen that the brace 20 not only forms a blocking device for locking the retainer closed, but, when the brace is moved from its blocked position, it is adapted to effect the opening of the retainer through the connections between the brace and retainer. Therefore the handle 29 by a comparatively 100 short movement in one direction, namely, forwardly, is able to first unblock the brace 20 and thereafter swing open the retainer, leaving the parts in the position shown in Fig. 2, while the reverse movement of the 105 handle 29, acting through the brace, first causes the retainer to swing closed and thereafter, upon reaching the position of Figs. 1, 3 and 4, blocks the brace and therefore locks the retainer shut. The described combination, therefore, attains the chief advantages hereinbefore recited.

Certain matters of preferred detail will now be described. In order to assist the operator to bring the parts accurately to 115 blocked position without going beyond such position, there may be provided an adjustable stop device consisting of a set screw 32 formed in a forwardly extending portion of the retainer or the fulcrum shaft swinging therewith, and adapted, when the parts are in closed position, to abut against a fixed portion of the machine frame, as best indicated in Fig. 3, a lock nut 33 serving to secure the set screw in its adjustment.

It will be understood that when the parts are in the position of Figs. 1, 3 and 4, the retainer is locked in closed position. The exact position of the free end or head 15 of the retainer arm is of some importance, and, 130

in order to accurately position it when the parts are locked, the following convenient adjusting means may be employed. The retainer arm at the point where it is rigidly connected to the fulcrum shaft 17 may be formed in two parts, namely, the lower and left-hand part 39, which is directly keyed to the fulcrum shaft and the part 40 from which the swinging arm actually extends. An adjusting screw 41 between the parts 39 and 40 permits slight relative adjustment between them, so that the arm may be initially accurately positioned. A lock nut 42 serves to lock the adjusting screw 41 against accidental displacement.

To limit the opening or outward swinging of the retainer, for example, to the position shown in Fig. 2, the crank stud 21 comes into contact with the abutment 24, as seen in Fig. 2.

The complete operation of the device will be readily understood from the above description.

The original adjustment of the device is simple. With the nuts 19, 33 and 42 loosened, the operator will first accurately position the retainer with respect to the shuttle, and will then close the screw 42 into contact with its fixed abutment. This forms a positive stop for the inward motion of the retainer. The lock nut 33 is then tightened to secure the screw 32. The screw 41 will then be turned or closed in order to effect a proper relative adjustment as between the brace 20 and the abutment 24. The operator will repeatedly try handle 29 while adjusting the screw until the parts are sufficiently tight to cause the brace to firmly cramp or bind against the abutment. The lock nut 42 will then be tightened to secure the screw 41 in place, and finally the nut 19 will be tightened to render the retainer substantially rigid with the fulcrum shaft 17. There will usually be insufficient wear to require a roller on the end of the brace, and any little wear is easily taken up by readjusting screw 41.

It will thus be seen that a retaining device has been described accomplishing the objects and attaining the advantages hereinbefore referred to, and other advantages will be apparent to those skilled in the art. Since many matters of form, combination, arrangement, design and detail may be variously modified without departing from the principles hereof, no limitations to such features are intended excepting so far as specified in the appended claims.

What is claimed is:

1. Retaining means for sewing machine shuttles comprising, in combination with a retainer swingable between closed and open positions, a brace eccentrically and movably mounted upon the retainer in a manner to permit shifting thereof relatively to the re-

tainer between blocked and unblocked position, and a permanently stationary blocking abutment adapted to block the brace and thereby prevent opening of the closed retainer.

2. Retaining means for sewing machine shuttles comprising, in combination with a retainer swingable between closed and open positions, a brace eccentrically and movably mounted upon the retainer in a manner to permit shifting thereof relatively to the retainer between blocked and unblocked position, and a blocking member normally disengaged from said brace and adapted to be engaged by and to block the brace when the retainer is closed, and the brace is in blocked position.

3. Retaining means for sewing machine shuttles comprising in combination with a retainer swingable between closed and open positions, a brace eccentrically and movably mounted upon the retainer in a manner to permit a limited shifting thereof relatively to the retainer, and a blocking abutment unconnected with said brace and adapted to be met by the brace and to block it against movement with the retainer, whereby to lock the retainer when the latter is closed, and a control handle so connected that one operative movement thereof unblocks the brace and thereupon opens the retainer.

4. Retaining means for sewing machine shuttles comprising, in combination with the stationary parts of the machine, a fulcrumed retainer arm having an eccentric pivot rigid therewith, and a rigid brace piece swingably mounted on said pivot, said brace shaped for manipulation and constructed and arranged to be cramped against a stationary part when the retainer is closed, so as to block the brace against movement with the retainer.

5. Retaining means for sewing machine shuttles comprising, in combination with the stationary parts of the machine, a fulcrumed retainer arm having an eccentric pivot rigid therewith, and a rigid brace piece swingably mounted on said pivot, said brace shaped for manipulation and constructed and arranged to be cramped against a stationary part when the retainer is closed, so as to block the brace against movement with the retainer, and said brace and retainer being constructed so that when the brace is unblocked, its swinging will swing the retainer open or shut.

6. A retaining device for sewing machine shuttles, comprising in combination, a retainer fitted to swing between closed and open positions, a brace pivotally connected to the retainer at an eccentric point, and adapted to swing into and from blocked position, and a stationary blocking member adapted to be engaged by said brace.

7. A retaining device for sewing machine

shuttles, comprising in combination, a retainer fitted to swing between closed and open positions, a brace pivotally connected to the retainer at an eccentric point, and adapted to swing into and from blocked position, and a stationary blocking member adapted to have the free end of said brace wedged against it.

8. A retaining device for sewing machine shuttles, comprising in combination, a retainer fitted to swing between closed and open positions, a brace pivotally connected to the retainer at an eccentric point, and adapted to swing into and from blocked position, and a stationary blocking member adapted to be engaged by said brace, and a handle for moving the brace to block and unblock it.

9. A retaining device for sewing machine shuttles, comprising in combination, a retainer fitted to swing between closed and open positions, a brace pivotally connected to the retainer at an eccentric point, and adapted to swing into and from blocked position, and a stationary blocking member adapted to be engaged by said brace, said brace being so connected to said retainer that swinging the brace may swing the retainer.

10. A retaining device for sewing machine shuttles, comprising in combination, a

retainer fitted to swing between closed and open positions, a brace pivotally connected to the retainer at an eccentric point, and adapted to swing into and from block position, and a stationary blocking member adapted to be engaged by said brace, said brace being so connected in a recessed part of said retainer that swinging the brace may swing the retainer.

11. A retaining device for sewing machine shuttles, comprising in combination, a retainer fitted to swing between closed and open positions, a brace pivotally connected to the retainer at an eccentric point, and adapted to swing into and from blocked position, and a stationary blocking member adapted to be engaged by said brace, said brace being so connected to said retainer that swinging the brace may swing the retainer, and a single handle movable for first unblocking the brace and then opening the retainer, and on the reverse movement effecting the closing of the retainer and blocking of the brace.

In testimony whereof I affix my signature in presence of two witnesses.

AUGUST R. SCHOENKY.
